UNITED STATES PATENT OFFICE.

FRANK L. O. WADSWORTH, OF SEWICKLEY, PENNSYLVANIA.

WATER-HEATER CONSTRUCTION.

1,146,826.

Specification of Letters Patent. Patented July 20, 1915.

Application filed October 24, 1912. Serial No. 727,510.

To all whom it may concern:

Be it known that I, FRANK L. O. WADSWORTH, a citizen of the United States, residing at Sewickley, in the county of Allegheny, and State of Pennsylvania, have invented certain new and useful Improvements in Water-Heater Construction, of which the following is a specification.

The invention relates to improvements in water heaters, and particularly to the automatic controlling mechanism therefor. It has for its primary objects, the provision of a combined pressure and thermostatic controlling means in which the number of parts is reduced to a minimum and a most compact arrangement of parts secured; and the provision of a controlling means in which the pressure and thermostatic means are closely and positively associated and a direct and reliable actuation of the gas valve is secured. Certain embodiments of the invention are illustrated in the accompanying drawings, wherein—

Figures 1 and 2 are front and side elevations respectively of a common form of instantaneous water heater, with one form of my improvement applied thereto; Fig. 3 is an enlarged longitudinal section through the combined thermostatic and water pressure controlling means employed in the construction of Figs. 1 and 2; Figs. 4, 5, 6, 8 and 9 are sections similar to that of Fig. 3, through modified forms of thermostatic and water pressure controlling means applicable to the heaters shown in Figs. 1 and 2 in place of the construction of Fig. 3; Fig. 6 is a perspective view of one of the operating bars employed in the construction of Fig. 5; Fig. 7 is a section on the line VIII—VIII of Fig. 5; and Fig. 10 is a section on the line XI—XI of Fig. 9.

The primary distinguishing feature of the present invention as compared with other constructions of which I am aware, wherein both thermostatic and pressure means operate a common gas valve, resides in the carrying of one of the controlling means bodily by the other, so that either the water-actuated element is shifted bodily by the thermostatic means and its effect upon the gas valve is modified by such bodily shift in position, or the thermostatic element is shifted bodily by the water-actuated means, and its effect upon the gas valve is modified by such bodily shift of position. My invention contemplates either of these broad al-

ternative constructions, and the various drawings forming a part of this specification illustrate a few of the various possible embodiments of the broad invention.

Referring first to the general arrangement of the heater parts as shown in Figs. 1 and 2; A is the casing of the heater; B indicates the upper coils of the heater; C is the lower reverse coil connected to the upper coils by means of the pipe D; E are the gas burners mounted upon the usual burner ring; F is the gas supply pipe; G is the casing of the gas valve for controlling the supply of the gas to the burners; H is the gas pipe leading from the gas valve casing G to the burner ring which carries the burners E; I is the casing of the water pressure controlling means; K is the casing of the thermostatic controlling means; L is the cold water inlet pipe leading from the main to the heater; M is the hot water outlet pipe leading to the house faucets; N is the hot water outlet pipe leading from the lower reverse coil C to the thermostat casing K, from which casing the water passes out through the house supply pipe M; and O is the usual pilot light connection leading to a pilot light (not shown) such as is common in all instantaneous heaters.

Referring now to Fig. 3 of the drawing in connection with Figs. 1 and 2, 1 is the water actuated pressure member carried by the casing I, such water actuated member being in the form of a piston held in its upper position by means of the spring 2. The upper side of this piston is exposed to water main pressure from the inlet pipe L, while the lower side of the piston has connection by means of the passage 3 with the pipe N of the heater, so that when the outlet from the heater is opened and the pressure therein reduced the piston 1 will move downward overcoming the pressure of the spring 2. A gas valve 4 is provided in the casing G normally held closed by the spring 5, and this valve is opened when the piston 1 moves down by means of the following connections. Piston 1 has screwthreaded to its lower interior portion the upwardly extending tube 6. This tube 6 has connected to it at its upper end the downwardly extending tube 7, such connection including the sleeves 8 and 9 to which both tubes are rigidly attached with the sleeve 9 slidably mounted in the packed collar 10 carried by the casing K. The sleeve 8 is preferably made of non-

conducting material so as to avoid as far as possible the direct communication of heat from the tube 6 to the tube 7. This sleeve may, however, be dispensed with and the two tubes joined by a single tube 9. The lower end of the downwardly extending tube 7 has secured thereto the block 11 which slides inside the tube 6 and carries the rod 12, such rod 12 serving to operate the thermostat levers 13. From the foregoing it will be seen that when the outlet from the heater is opened and the piston 1 moves down the tubes 6 and 7 with the rod 12 carried thereby will move down and actuate the thermostat lever 13 to open the gas valve 4, thus admitting a supply of gas to the burners to heat the water flowing through the coils of the heater. As the piston 1 moves down its tapered inner surface moves away from the tapered plug 14, thus permitting the water to flow through the slots 15 in the lower end of the tube 6, and the opening 16 through the end of the block 11 to the interior of the tube 7. Passing up through this tube 7, the water enters the short connection 17 leading to the top coil B of the heater (Fig. 1). The ball check valve 18 at the lower end of the tube 7 serves to prevent any backflow of water through such tube 7.

The manner in which the thermostatic control is secured will now be readily understood. The tube 6 is preferably made of a material having a high coefficient of expansion, and the hot water flowing from the pipe N to the pipe M passes around the tube 6 and causes it to contract or expand, according to the temperature of the outflowing water. If while the piston 1 is down and the main gas valve 4 is open, water being at such time withdrawn from the heater, such water rises above the predetermined temperature for which the thermostat is set, the tube 6 will expand and move the tube 7 upward a sufficient distance to withdraw the rod 12, thus permitting the spring 5 to close the gas valve and shut off the supply of gas to the burners. When the temperature of the flowing water once more falls below the point of thermostatic cut off the contraction of the tube 6 will move the tube 7 and the rod 12 downward and once more open the gas valve, admitting a fresh supply of gas to the main burner where it will be ignited.

In order to permit a circulation of the water in the coils of the heater when the outlet from the pipe M is not open, the valve 19 is provided, such valve being actuated by the spring 20 and being normally held in the position indicated in Fig. 3 when the piston 1 is in its upper position, that is, when no water is being withdrawn from the heater. At this time it will be seen that the water heated in the lower reverse coil C by the pilot burner will circulate upward, passing out at the connection N, up through the casing K around the thermostat tube 6, past the valve 19 and back through the passage 17 to the upper coil B of the heater. A continuous circulation is secured in this manner even when the outlet from the heater is not opened. At other times when the outlet from the pipe M is open, the valve 19 will be closed, thus preventing incoming cold water from the tube 7 from by-passing from the upper end of such tube to the pipe M.

To summarize briefly, the operation is as follows. Starting with the water in the heater at a temperature below its predetermined point, with the outlet from the pipe M closed, and with the parts in the position indicated in Fig. 3. If now the outlet from the pipe M be opened, the pressure upon the lower side of the piston 1 will be reduced by virtue of the connection 3, and the piston will move down under the influence of the pressure from the main. As the piston 1 moves down the water supplied from the inlet pipe L passes through the slots 15, the opening 16, and up through the tube 7 to the inlet 17 of the heater, the valve 19 at such time being permitted to close by reason of the downward movement of the tube 6 carried by the piston 1. This downward movement of the tube 1 also moves down the tube 7 carried by the tube 6, thus causing the rod 12 to engage the thermostat lever 13 and open the valve 4. Gas is thus admitted to the burner of the heater, and the water, flowing from the connection 17 through the upper coils B and the lower reverse coils C to the connection N is heated, such water then passing up through the casing around the thermostat tube 6 to the outlet pipe M. If now water flowing through the casing K to the outlet M becomes heated to too high a temperature, the expansion of the tube 6 will carry the tube 7 and the rod 12 upward, thus permitting the spring 5 to close the gas valve and shut off the supply of gas to the burners. Similarly, if the piston 1 is accidentally stuck in open position after the outlet from the heater is closed. Under such conditions due to the nonsupply of cold water to the heater, the water in the heater will become overheated, thus causing the expansion of the thermostat tube 6 to such an extent that the tube 7 and the rod 12 will be moved upward, thus permitting the gas valve 4 to close. An added safety control is provided by the use of the ball check valve 18 which prevents any backflow of the water from the heater coils into the cold water supply pipe and causes the expansion of the water itself to act upon the under side of the piston 1, thus forcing it to its closed position and lifting all of the parts out of engagement with the gas valve lever 13. It will be noted that in the construction just described the thermostatic 120

125

130

element 6 is carried bodily by the water actuated element 1, and that the construction by reason of this arrangement is very compact and simple, and that the operation is absolutely positive. It will also be noted that the necessity for the counterbalancing springs and other complicated mechanism ordinarily required where there is a single valve controlled both by thermostat and by a water pressure member is thus dispensed with.

Fig. 4 illustrates a very compact form of apparatus wherein the thermostatic element is carried by the water actuated element as in the types of apparatus heretofore described, the thermostatic element being in this case a liquid one of the corrugated box type. In this apparatus F² is the gas supply pipe; G² is the gas valve casing which carries the gas valve 4² and the spring 5² for normally holding the valve closed; H² is the gas pipe leading from the gas valve casing to the burners of the heater; K² is the casing containing the water actuated piston 1²; L² is the cold water supply pipe leading into the casing K²; 17² is the outlet from the casing K² leading to the top coil of the heater; N² is the connection leading from the lower reverse coil of the casing K²; M² is the hot water outlet pipe from the apparatus; and 7² 7² are a pair of concentric corrugated thermostat tubes, the opening between which is filled with some liquid having a relatively high coefficient of expansion. The piston 1² is in the form of a box having an inlet port 36 opposite the end of the connection N², and an outlet port 37 at the forward end of the piston, between the plate 38 and tube 39. The piston 1² is normally held in the position shown by means of the springs 40 and 41. The port 42 provides for communication between the pipes L² and 17² when the piston moves to the right upon the opening of the outlet from the heater, and the port 43 leading to the recess around the periphery of the piston provides for a communication between the pipes N² and 17² when the outlet from the heater is closed, so that a continuous circulation from the bottom to the top coils of the heater may be secured when no water is flowing from the heater. The front ends of the thermostat tubes 7² are secured to the plate 38 of the piston, and carry at their rear ends a plate 44 secured to the tube 39, such tube 39 being perforated as indicated, to provide for the passage of water to the outlet port 37. The tube 39 is secured at its front end to another tube 45 closed at its rear end and carrying the rod 46, such rod 46 being adapted to engage the stem 47, Stem 47 is provided with a split collar 48 adjustable on the rod and adapted to engage the stem of the gas valve 4². The flange 49 serves as a stop for limiting the forward

movement of the piston, and is provided with perforations 50 to permit of the passage of water from the interior of the piston to the pipe N² when the plate 38 is against the stop flange. It will be seen that the position 70 of the rod 46 from which the gas valve is operated is regulated by the expansion and contraction of the liquid in the thermostat tubes 7² which are free to expand rearwardly carrying the plate 44 and the rod 46 75 to the left as the temperature of water inside the piston rises, and are also free to contract under the water pressure, carrying the said plate and rod to the right as the temperature falls.

When the outlet from the pipe M² is opened the pressure upon the front side of the piston is reduced and it moves forward, uncovering the port 42 and permitting a flow of water through the heater. This forward 85 movement of the piston causes the rod 46 to engage the rod 47, and this rod in turn engaged the stem of the gas valve and opens it. As in the case of the mechanisms previously described, the parts are so adjusted 90 that this opening of the gas valve occurs just prior to the arrest of the valve actuated member and the parts carried thereby, by the stop provided for that purpose—in this case by the stop member 49. The water 95 from the heater passes through the connection N² and through the port 36 into the interior of the piston 1². The water thus supplied to the interior of the piston circulates past the thermostat casing 7², passing 100 through the perforations in the tube 39 and out at the front end of such tube, from which point it passes to the pipe M². If the water in the piston rises above a predetermined temperature the expansion of the casing 7² carries the plate 44 and the rod 46 to the rear far enough to allow the gas valve to close. When the temperature falls the contraction of the liquid in the thermostat box allows this box to shorten under the 110 pressure of the water and thus move the rod 46 to the right and once more open the gas valve. The thermostatic action of the liquid in the box formed by the tubes 7² 7² can be supplemented if desired by making 115 the tube 45 of some material having a high coefficient of expansion and the rod 46 of material with a low coefficient of expansion. When the piston 1² is in its forward position the circulation port 43 is covered so that the 120 cold water from the pipe 17² cannot bypass around the piston to the port 36.

Fig. 5 illustrates another modification of the invention, the arrangement as heretofore described, however, being reversed in that 125 the water actuated member is carried by the thermostat instead of the thermostat being carried by the water actuated member. In this apparatus the water actuated member is a diaphragm instead of a piston, and 130

the thermostat is a compound one made up of rods and tubes arranged in compact form and designed to give a relatively large amount of movement for the changes in the 5 temperature of the water. In this apparatus F^3 is the gas supply pipe leading into the casing G^3 provided with a gas valve 4^3 and the spring 5^3 for holding the valve in closed position; H^3 is the pipe leading to the gas 10 burners; K^3 is the casing containing the controlling mechanism; L^3 is the cold water inlet pipe; 17^3 is the pipe leading from the casing to the top coils of the heater; N^3 is the connection leading from the lower 15 reverse coil of the heater to the casing; 7^3 is the thermostat past which the water from the connection N^3 flows on its way to the hot water outlet pipe M^3 ; and 1^3 is the diaphragm of the water actuated member. 20 The water actuated diaphragm 1^3 carries a tube 52 provided with perforations 53 and a screw cap 54 which in turn carries the stem 55 having a lost motion connection with the stem of the valve 4^3 . The casing 25 51 is normally held in its rearmost position by means of the spring 56 , and at its front end has a collar 57 which makes a sliding packed engagement with the walls of the chamber 58 with which the pipes L^3 and 30 17^3 communicate. The diaphragm 1^3 is normally held in its forward position by means of the spring 59 , and when such diaphragm is in its rear position the rear end of the tube 52 is closed by the valve stop 60 . Communication 35 between the interior of the casing 51 and the chamber surrounding the casing is had through the perforations 61 . The thermostat 7^3 consists of a plurality of tubes $61, 62, 63, 64, 65, 66, 67$, and 68 alternating with bars $67'$ having their ends hooked in opposite directions as indicated at 40 70 and 71 (Fig. 6). The inner tube 61 is screw threaded at its front end to the casing 51 , while at its rear end is slidingly guided 45 upon the projecting head 72 , while the outer tube 68 is secured at its rear end to the casing K^3 . It will be seen that an expansion of the outer tube 68 will carry the front end of such tube forward and thus carry 50 with it the hooked end of the bar 67 . The position of the other end of this bar 67 fixes the position of the next tube 62 , and the action of this tube with respect to the next tube is the same as that just described. 55 As a result a multiplication of movement is secured, the inner tube 61 being moved a distance equal to the sum of the changes in length of the connecting bars 67 , it being understood that the materials from which 60 the tubes and bars are made is selected so as to give as large a difference in the coefficient of expansion as is possible. From the foregoing it will be seen that the gas valve is actuated by the movement of the 65 diaphragm 1^3 , but that the actuation of the

gas valve by the diaphragm is governed by the position of the casing 51 carrying the diaphragm, and that such position is controlled by the thermostat.

When the outlet from the pipe M^3 is 70 opened the pressure on the right hand side of the diaphragm 1^3 is reduced by reason of the port 61 , and the pressure on the front side of the diaphragm overbalancing that on the rear side, the diaphragm moves to the right until it is stopped by the valve head 60 , the parts being so adjusted that the final movement opens the gas valve and permits a flow of gas to the burners of the heater. At this time water flows from the pipe N^3 past 75 the thermostat 7^3 to the hot water outlet pipe M^3 , thus giving a control of the thermostat by the outflowing water. If now the temperature of the outflowing water rises above a predetermined point the inner tube 61 carrying the diaphragm casing 51 moves to the left, carrying with it the diaphragm and so permitting the gas valve to be closed by the spring 53 thus shutting off the gas supply. When the temperature of 80 the flowing water falls the differential contraction of the thermostat elements moves the casing and its attached parts to the right, thus pulling open the gas valve and admitting a fresh supply of fuel to the main 85 heating burners.

When the outlet from the heater is closed and the parts are restored to the position shown in Fig. 5 the perforated tube 52 permits the water to circulate between the outlet pipe N^3 and the inlet pipe 17^3 , but this connection is cut off when the outlet from the heater is opened and the diaphragm 1^3 moves to the right, as at such time the valve 90 60 closes the end of the tube 52 . The arrangements of the bars 67 with respect to the tubes will be readily understood by reference to Fig. 7 which shows the bars and tubes in cross section.

Fig. 8 illustrates another arrangement 100 wherein the position of the water valve is regulated by means of the thermostat, the movable water actuated means being carried in such case by the thermostat as in the construction of Fig. 5. In this apparatus F^4 is the gas inlet pipe leading to the valve casing G^4 provided with the gas valve 4^4 and the spring 5^4 for holding the valve closed; H^4 is the gas pipe leading to the burners of the heater L^4 is the cold water inlet leading to the casing K^4 ; 17^4 is the connection leading to the top coil of the heater; N^4 is the connection leading from the lower coil of the heater, and M^4 is the hot water outlet pipe. The water actuated member in this 110 case is a piston 1^4 which is normally held in forward position by means of the spring 72^4 , the casing 73 which carries the piston 1^4 being itself slidably mounted in the casing K^4 and being carried by the thermostat 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920

as hereinafter described. The piston 1⁴ has lost motion connection with the gas valve 4⁴ by means of the stems 74 and 75 adapted to coöperate as indicated in the drawing. The 5 wall of the member 73 is provided with a port 76, and the wall of the casing K⁴ is provided with a passage 77 leading upward, whereby communication is had through the upper portion of the casing K⁴ to the connection 17⁴ leading to the top of the heater. The expansible portion of the thermostat 10 consists of a pair of concentric corrugated tubes 78 and 79 secured at their upper ends to the casing K⁴ and at their lower ends to the upper end of the casing 73, so that the 15 position of the lower end of the corrugated tubes regulates the position of the casing 73 which carries the water actuated member 1⁴. Communicating with the upper end of the 20 annular chamber formed between the members 78 and 79 is another annular chamber formed by the tubes 80 and 81 connected together at their upper ends by means of the collar 82 which slides in the union 83. These 25 two communicating chambers are completely filled with a liquid having a high coefficient of expansion such as petroleum; paraffin oil, etc. Ports 84 and 85 form a means of communication from the connection N⁴ to the 30 interior of the tube 81, and the upper end of this tube 81 communicates with the outlet pipe M⁴. The ports 86 in the upper end of the member 73 provide a means whereby the 35 upper side of the water actuated piston 1⁴ is exposed to the pressure of the water in the heater. From the foregoing it will be readily understood that the position of the casing 73 of the water actuated member is regulated and governed by the thermostat, and 40 that the movement of such member 73 is determined by the expansion and contraction of the liquid in the chamber formed by the corrugated tubes 78 and 79 and the tubes 80 and 81.

45 In operation, when the outlet from the heater is opened, the pressure upon the upper side of the piston 1⁴ is reduced and the piston moves upward, thus uncovering the port 76 and permitting a flow of water through 50 such port to the passage 77 and thence upward to the connection 17⁴ leading into the heater. This upward movement of the piston 1⁴ causes the opening of the gas valve 4⁴ and permits a flow of gas to the burners 55 of the heater, the upward piston movement being arrested and determined by the engagement of the piston hub with the head of the casing 73. If during the operation of the apparatus the temperature of the water 60 becomes too great the liquid in the chambers between the tubes 78 and 79, and 80 and 81, expands, causing the lower ends of the tubes 78 and 79 to move downward and shifting the position of the casing 73 downward. 65 This of course changes the position of the

piston 1⁴ and permits the valve 4⁴ to close. It will also be seen that should the piston 1⁴ stick in its upper position a similar result will be secured, the expansion of the liquid in the thermostat causing the casing 76 to move down, permitting the closing of the gas valve. When the temperature falls there is a reverse or reciprocal movement of the casing which allows the gas valve to be again opened by the pressure on the valve 75 actuated element 1⁴.

When the piston 1⁴ is in its lowest position the upper edges of the ports 76 are uncovered, thus allowing a free circulation 80 of the water through the heater coils from the outlet N⁴, the parts 84, 86, 76 and 77, to the inlet 17⁴. When the piston is raised this circulation is prevented, by the covering of the upper edges of the ports 76 by 85 the piston.

Figs. 9 and 10 indicate another modification of the apparatus, in which the water 90 actuated member is carried by the thermostat, the water actuated member in the present case being a diaphragm instead of a piston. In this construction H⁵ is the gas inlet pipe leading to the casing G⁵ provided with the gas valve 4⁵ held normally in closed position by the spring 5⁵; F⁵ is the pipe leading from the gas valve casing to the burners; K⁵ is the casing containing the controlling mechanism; L⁵ is the cold water inlet pipe from the main leading into the casing; 95 17⁵ is the connection leading from the casing K⁵ to the upper coil of the heater; N⁵ is the connection leading from the lower coil of the heater for conducting the hot water to the casing K⁵; M⁵ is the hot water outlet pipe; and 1⁵ is the water actuated diaphragm. In this type of apparatus the thermostat consists of the corrugated tube 86 connected at its rear end with the four pipes 87, the tubes 86 and 87 being filled with a liquid having a relatively high coefficient of 100 expansion, and the tubes having a communicating cap 86 at the upper end. The volume of the liquid in the thermostat may be adjusted by means of the screw 89. The front end of the corrugated tube 86 carries the casing 90, which casing 90 supports the diaphragm 1⁵ and is packed for longitudinal movement in the casing K⁵. A valve member 90^a governs communication between the pipes L⁵ and 17⁵, such valve being carried by the diaphragm 1⁵ and having an opening 110 therethrough as indicated at 91. The opening at 91 is controlled by the valve 92 carried by the casing 90, the arrangement being such that when the outlet from the heater is closed the diaphragm 1⁵ occupies the position illustrated in Fig. 10, and the passage 91 through the valve 90 is opened. The valve 90 is provided with the stem 92^a normally held in the position shown, by means 115 of the springs 93, and such stem has a lost 120

125 130

motion connection with the stem of the gas valve 4⁵. The member 90 carrying the diaphragm is perforated as indicated at 94, so that the pressure in the heater is applied to the rear side of the diaphragm, while that from the inlet pipe L⁵ is supplied to the front face of the diaphragm.

If now the outlet from the heater is opened, the pressure upon the rear side of the diaphragm 1⁵ is reduced and the valve 90 carried by the diaphragm moves to the left, thus permitting a flow of water from the pipe L⁵ to the pipe 17⁵ and through the heater, the water as it flows from the lower 15 coil of the heater passing through the connection N⁵ and the casing K⁵ to the hot water outlet pipe M⁵. Movement of the diaphragm 1⁵ to the left causes the opening of the gas valve 4⁵, permitting a supply of 20 gas to pass to the burners of the heater, the movement being arrested as before, by the engagement of the valve member with the valve 92 on the casing 90. If during the operation of the heater the water flowing 25 through the casing K⁵ rises above the predetermined temperature for which the thermostat is set, the expansion of the liquid in the thermostat causes the right hand end of the corrugated tube 86 to move to the right, thus 30 moving the member 90 which carries the diaphragm 1⁵ to the right and permitting the gas valve 4⁵ to be closed by its spring 5⁵. The lowering of the temperature produces a reverse or backward movement of the casing, thus allowing the gas valve to be again 35 opened by the action of the water actuated diaphragm member 1⁵. When the outlet from the heater is closed and the diaphragm is returned to its normal position by the 40 spring 93 the valve 92 is open and the water is permitted to circulate between the inlet and outlet of the heater only through the 45 openings 91 and 94.

In all the above forms of apparatus the 45 temperature at which the thermostat acts to cut off the gas may of course be adjusted as desired, by adjusting the amount of lost motion between the gas valve stem and the parts engaging therewith, or by adjusting 50 the position of the stops which determine the opening movement of the water actuated member, or by joint adjustment of both of the aforesaid parts.

Having thus described my invention and 55 illustrated its use, what I claim as new and desire to secure by Letters Patent, is the following.

1. In an automatic water heater, a burner, a gas valve for controlling the supply of 60 gas to the burner, water actuated means and thermostatic means for controlling the gas valve, with one of the said means carried bodily by the other means, the water actuated means being arranged to open the 65 gas valve when the outlet of the heater is

opened and the temperature of the water below a predetermined point, and the thermostatic means being arranged to close the gas valve without moving the water actuated means with respect to the means which carries it when such valve is open and the temperature of the water rises above a predetermined point.

2. In an automatic water heater, a burner, a gas valve for controlling the supply of gas 75 to the burner, water actuated means and thermostatic means for controlling the gas valve, each of which has a movable element for controlling the gas valve by such movement, with one of said means carried bodily by the movable element of the other means, the water actuated means being arranged to open the gas valve when the outlet of the heater is opened and the temperature of the water below a predetermined point, and the thermostatic means being arranged to close the gas valve without moving the water actuated means with respect to the means which carries it when such valve is open and the temperature of the water rises above a 80 predetermined point.

3. In an automatic water heater, a burner, a gas valve for controlling the supply of gas to the burner, a movable member actuated by differences of water pressure caused by opening and closing the outlet from the heater and arranged to operate the gas valve, a thermostatic member governed by the heated water and having a part adapted to move back and forth on variations of temperature in the water of the heater, and a connection between the said thermostatic part and the gas valve, one of the said members being carried bodily by the other member whereby its operation is controlled by such other member, the thermostatic member being arranged to operate the gas valve without moving the water actuated member with respect to the means which carries it.

4. In an automatic water heater, a burner, a gas valve for controlling the supply of gas to the burner, pressure mechanism including a reciprocating controlling member whose position is governed by differences of water pressure caused by opening and closing the outlet from the heater, a controlling thermostatic member secured to one of the parts of the pressure mechanism, and a connection between the gas valve and one of the said controlling members, the thermostatic means being arranged to operate the gas valve without moving the said controlling member with respect to the means which carries it.

5. In an automatic water heater, a burner, a gas valve for controlling the supply of gas to the burner, a movable water actuated member, and a thermostatic means carried bodily by the water actuated member and 120

- provided with an element for opening the gas valve, the parts being arranged so that when the outlet from the heater is opened and the temperature of the water below a predetermined point the movement of the water actuated member causes the thermostatic element to open the valve, the said element also being moved back and forth to effect changes in the position of the gas valve by changes in temperature of the water without moving the water actuated member.
6. In an automatic water heater, a burner, a gas valve for controlling the supply of gas to the burner, a movable water actuated member, and a thermostatic means carried bodily by the water actuated member and provided with an element for opening the gas valve, the parts being arranged so that when the outlet from the heater is opened and the temperature of the water below a predetermined point the movement of the water actuated member causes the thermostatic element to open the valve, the said element also being moved back and forth to effect changes in the position of the gas valve by changes in temperature of the water without moving the water actuated member, and there being a lost motion connection between the said element and the gas valve.
7. In an automatic water heater, a burner, a normally yieldingly closed valve for controlling the supply of fuel to the burner, a movable member actuated by changes of water pressure when the outlet from the heater is opened, a thermostat carried bodily by the said member and provided with an element for opening the gas valve when the outlet from the heater is opened and the movable member and thermostatic element are moved forward, the said element also being moved back and forth to effect movements of the gas valve and without a movement of the pressure actuated member by changes of temperature of the water.

In testimony whereof I have hereunto signed my name in the presence of the two subscribed witnesses.

FRANK L. O. WADSWORTH.
